INVENTOR

Michael O'Gorman
BY
R. A. Darr
ATTORNEY

UNITED STATES PATENT OFFICE.

MICHAEL O. GORMAN, OF JERSEY CITY, NEW JERSEY.

AUTOMATIC GAS-GOVERNOR.

SPECIFICATION forming part of Letters Patent No. 310,580, dated January 13, 1885.

Application filed April 11, 1884. (No model.)

To all whom it may concern:

Be it known that I, MICHAEL O. GORMAN, a citizen of the United States, and a resident of Jersey City, in the county of Hudson and State of New Jersey, have invented certain new and useful Improvements in Automatic Gas-Governors, of which the following is a specification.

My invention relates to that class of gas-governors in which an inverted cup floats in mercury for operating the valve which regulates the flow of gas from the meter.

The object is to properly guide the valve and simplify the construction, thereby lessening the cost.

Referring to the drawings, Figure 1 represents side elevation in sections, Fig. 2 a plan of same with cover removed.

a represents case provided with passages or ports, *b* for inlet and *c* outlet. *d* is a valve attached to stem *e*, which passes through guide *f*, placed in the chamber *b*, above the valve *d*, and also passes through the guide *g* in the dome *h* of case *a*, and then secured to the inverted cup *j k*. On the top of said cup is placed the weights *l*, to regulate the flow of gas through the valve *d*.

In the circular mercury-chamber *m*, formed by the case *a* and dome *h*, is placed the ring *o*, between the smaller and larger cup *j k*, for displacing a portion of the mercury. The said ring *o* is secured to the bottom of the chamber *m* by screws, over the port *n*, which passes through both the bottom and the ring. By the ring *o* two separate chambers are formed for the large and small cup, respectively, and the said chambers are connected, so as to equalize the height of the mercury in each, by the passage *p* between the bottom of

chamber *m* and ring *o*. The said passage extends around under the ring except where it is fastened to the bottom. (Shown by dotted lines in Fig. 2.)

On the top of the case *a* is fitted a cap, *q*, and sealed or secured by means of pins or locks in lugs on the outside of case *a*. The object of this cap is to keep out the dirt, and is sealed to prevent unauthorized persons from tampering with same.

The operation is as follows: The gas from the meter passes into the opening or inlet *b*, through the valve *d*, out into the outlet *c*. If the pressure of gas exceeds the amount consumed, it passes up into the dome *h* through the openings *x x*, and lifts the small cup *j*, and partly closes the valve *d*. Should this be insufficient to regulate the flow of gas, the gas will then enter the port *n* and exert a greater force on the valve *d* by lifting the large cup *k*, the amount of pressure being always regulated by the balance-weight *l*, and the valve-stem *e* being guided by bars *f* and *g* the valve will always be sufficiently closed.

What I claim, and desire to secure by Letters Patent, is—

In a gas-pressure regulator, the guide *g*, placed in the top of dome *h*, and guide *f* in the chamber *b*, in combination with the valve-stem *e* and case *a*, substantially as and for the purpose specified.

Signed at New York, in the county of New York and State of New York, this 8th day of April, A. D. 1884.

MICHAEL O. GORMAN.
